(57) **CLAIM**

The ornamental design for a fume extractor, as shown and described.

DESCRIPTION

FIG. 1 is a front perspective view of a fume extractor according to an embodiment of the present invention; FIG. 2 is a rear perspective view of the fume extractor of FIG. 1;

FIG. 3 is a front side view of the fume extractor of FIG. 1; FIG. 4 is a left side view of the fume extractor of FIG. 1; FIG. 5 is a right side view of the fume extractor of FIG. 1; FIG. 6 is a top view of the fume extractor of FIG. 1; and,

FIG. 7 is a rear side view of the fume extractor of FIG. 1; and, FIG. 8 is a bottom view of the fume extractor of FIG. 1. The broken line showing of environmental structure in FIGS. 1 and 5-8 is for illustrative purposes only and forms no part of the claimed design.
